Primary Examiner — Paula Greene(74) *Attorney, Agent, or Firm* — Irina Hass(57) **CLAIM**

The ornamental design for a handle, as shown and described.

DESCRIPTION

FIG. 1 is a perspective view of a first embodiment of a handle showing the new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines in the drawings are shown for illustrative purposes only and form no part of the claimed design.

1 Claim, 2 Drawing Sheets(56)
